MINE ROOF BOLTS
William E. Worley, 291 Avon Road,
Devon, Pa. 19333
Filed Mar. 30, 1966, Ser. No. 538,807
11 Claims. (Cl. 85—79)

This is a continuation-in-part application of my prior application Serial No. 446,886, filed April 9, 1965, and entitled "Mine Roof Bolts," now abandoned.

The present invention relates to means for supporting roofs of mines and more particularly to a novel improvement in roof bolts used for this purpose and the method of making these bolts.

Since the inception of underground mining, the need to support the overhead ceiling or roof in the underground passageways of a mine has been recognized as essential in order to prevent failure or collapse of the roof thereby jeopardizing the lives of men working in the underground mine. Thus, the problem of safe and adequate roof support is a very serious one. One of the oldest supports employed is use of timbers or other similar support means such as masonry walls and arches, steel timber sets, metal props, steel and masonry supports and others. These installations are comparatively expensive due to the cost of the support materials and mainly the high installation costs. Moreover, the beam supports are cumbersome and take up valuable space in the mines. Additionally, it has been found that in some instances activity in the strata or layers above the mine roof sets up forces which the timber supports cannot withstand and cave-ins result.

A more recent development in this area is the use of elongated roof bolts which are inserted into openings drilled in the strata above the roof of a mine passageway at predetermined spaced apart intervals. These bolts are usually three to four feet long and are mounted in vertical holes drilled into the ceiling. These bolts conventionally include some type of anchor-like fastening means at one end adjacent the uppermost part of the hole and means at the opposite end of the bolt to place the bolt under tension. By this arrangement it was thought that the strata above the roof would be compressed in a vertical direction whereby several thinly bedded bands or strata of rock or other material above the roof level would be bound together by means of the bolts to simulate a thicker strata which would be sufficiently strong to prevent flexure of the roof. In other words, the pattern of roof bolts in the roof was thought to secure weak roof material to strong massive overlying rocks or to reinforce the immediate roof strata to form a laminated beam. However, in certain situations, for example, where the roof strata does not have a solid rock layer for anchorage, this type of bolt has not provided adequate roof support. An important factor in this regard is that by compressing the strata vertically, only the tension component of shear is supported while the compression component is not supported. Further it has been found that if the anchor is located in soft areas of the strata above the roof, the anchor slips and the roof starts to sag or bulge in the areas between the bolts and in some cases the entire roof has ultimately failed.

In order to provide optimum support for the roof strata, it is important that the strata supported by the roof bolts be held firmly in place. It has been found that comparatively small initial movements of the strata has a compounding effect which ultimately leads to larger movements of the strata and movement of adjacent strata and eventually to complete failure of the roof. Further, it has been found that the presently used roof bolts do not support the strata in a manner to resist this initial movement. More specifically it has been observed that anchor slippage with these prior bolts and bolt elongation by

2

reason of the great distance between the anchor and the other terminal end of the bolt permit small movement of the strata which, as noted above, can lead to complete failure of the roof.

5 One prior roof bolt of the type discussed above is known as the slot and wedge bolt. This bolt comprises an elongated rod which has a tapered opening in its upper end to receive a wedge block and is threaded at its lower end. This bolt is installed in a hole in the mine roof by driving the wedge block against the top of the hole so that it expands the upper end of the rod into engagement with the side wall of the hole to provide anchor means. A plate is placed over the threaded end of the rod and a nut is applied to the threads to tension the bolt. One of the shortcomings of this type of bolt is the fact that it has to be driven into the hole which could disrupt the mine roof and set up forces which weaken the roof. Additionally, the hole in the mine roof has to be a predetermined fixed depth and requires a firm top in order to provide 10 a strong surface against which the wedge block engages. Moreover, since the anchor end in its expanded condition is of a larger diameter than the rod, a considerable amount of space exists between the hole and the rod throughout its length thereby permitting horizontal or lateral shifting of the strata and thus failing to resist the compression component of shear stress for a major portion of the bolt. Further, it is clear that this type of bolt is difficult to remove from the mine roof and is not suitable for reuse.

Another former type of expansion bolt discussed above 30 is the bail-type expansion unit. This unit comprises an elongated bolt which is threaded at its inner end and has a head at its other end to accommodate a wrench for turning. An internally threaded wedging plug is adapted to be mounted on the threaded end of the bolt and upon 35 downward movement, engages internally of a split sleeve to wedge it outwardly whereby an outer serrated surface of the sleeve grips the wall of the hole and serves as an anchor. In preparing this bolt for installation, a roof plate has to be assembled prior to application of the sleeve and this is usually done at the mine site. After the unit 40 is inserted up into the hole, the head is turned, whereby the tapered plug is threaded downwardly along the top end of the bolt and spreads the wings or leaves of the sleeve outwardly to engage the wall of the upper portion of the hole. This anchors the bolt at the upper end and continued turning of the head places the bolt under tension. As noted above, theory of this type of support is that a series of these bolts will compress the 45 layers of the material above the roof vertically to compact the roof strata to form a laminated beam. One of the problems with this type of bolt, however, is that the expansion anchor provides a relatively small contact area with the wall of the hole, and if the material surrounding the anchor end is not firm, the sleeve tends to 50 slip and slippage can eventually lead to failure of the roof. Furthermore, small strata movements produce elongation which also could result in failure of the roof. Moreover, this conventional type of bolt only supports the tension component of shear stress in the layers above 55 the roof. Furthermore, the bolts are difficult to remove and often are damaged upon removal and thus, are not generally suitable for reuse.

Another prior type of expansion bolt is the type comprising an elongated rod having a hollow shell portion at 60 its inner end within which is contained a small explosive charge. This bolt is inserted into a hole in the mine roof and the small explosive charge is set off to expand the shell into engagement with the wall of the hole at the inner end thereof and serve as an anchor. A bearing plate is then positioned over the lower threaded end of the bolt and a nut is applied to place the bolt under tension. The principle of support of a series of bolts

of this type is the same as that outlined above. In other words, a series of spaced bolts are designed to compress the roof strata vertically thereby compressing the layers above the roof into the form of a beam. However, it is apparent that if slippage takes place or if the bolt is overstressed, there is the danger of roof failure. Moreover, it is readily apparent that this type of bolt is not reusable. Additionally if the upper portion of the hole is not a solid layer, the anchor will not grip firmly and slippage is inevitable. Further as is noted above, this type of support only resists the tension component of shear stress and not the compression component by reason of the fact that there is only a comparatively small contact area between the anchor sleeve and the wall of the hole.

With the foregoing in mind, the principal object of the present invention is to provide a bolt for supporting the roof of mines which is characterized by novel features of construction and arrangement to provide a firm support for the roof and which is highly economical to manufacture and install. The bolt of the present invention supports the roof strata firmly and resists initial small movements of the strata much more effectively than prior bolts by reason of the fact that anchor slippage is practically eliminated and the effect of bolt elongation is localized. The bolt of the present invention engages the side wall of the hole at a plurality of contact zones throughout the length of the bolt thereby providing a plurality of anchor points as contrasted with the prior bolts discussed above which have only a small contact with the side wall of the hole at the upper end thereof. Additionally, whereas localized strata movement effected elongation of the entire rod in prior bolt constructions, localized strata movements effect small elongation of the bolt of the present invention by reason of the many longitudinally spaced contact zones. Thus, the effect of the bolt of the present invention is to strongly resist strata movement which is the major cause of roof failure.

The bolt of the present invention comprises broadly a pair of elongated bars of stepped configuration having confronting, longitudinally extending faces, each face having a plurality of planar angularly disposed longitudinally spaced cam surfaces which in the stacked position of the bolt are in overlying, confronting engagement. Each of the bars has a stepped outer face opposite the cam face provided by a plurality of cutout sections defining a plurality of projections forming contact points or zones.

One of the elongated bars has a threaded shank depending from one end thereof and the other bar has an axially extending depending stem portion which, when the engaging cam surfaces overlie one another, confronts a portion of the threaded shank. When installing this bolt, the bars which are in a stacked position are inserted up into a hole in the roof, the hole being of a slightly greater cross section than the opposed contact zones. The bars are now displaced longitudinally relative to one another, whereby the opposed contact zones are displaced radially relative to one another due to the cooperating cam surfaces to engage diametrically opposed areas of the side wall of the hole at a plurality of longitudinally spaced points the entire length of the hole. The bars may be displaced by placing a bearing plate over the threaded shank to engage the lower end of the stem and then applying and turning a nut on to the shank whereby one bar member is drawn downwardly and the contact points are moved laterally apart to engage the side wall of the hole at a plurality of longitudinally spaced points as shown in FIG. 5 of the drawings. By this arrangement, there is a large contact area with the wall of the hole along the entire length thereof, thus eliminating the possibility of slippage of the bolt in the hole. Accordingly, when a series of spaced bolts is inserted into the roof, the various layers are compressed laterally whereby the bolts support the compression as well as the tension com-

ponent of shear stress in the roof layers. Thus, by essentially filling the hole in the mine roof, lateral movement of the various layers of the roof is resisted and a safe roof is provided. Moreover, unlike the prior bolts discussed above, the roof top need not be solid to firmly anchor the bolt against slippage. Additionally if there are projections or irregularities along the side wall of the hole into which the bolt is inserted, the localized contact areas of the bolt exert a great compressive force to crush the projection thereby insuring a good firm anchorage of the bolt in the hole.

The principle of operation of the bolt of the present invention is entirely different from the bolts discussed above and does not rely on tensioning of the bolt as the sole means of support. However, since the bolt of the present invention is vertically oriented and is anchored essentially throughout its length with the strata of the roof, it effectively supports the tension components of shear stress as well as the compression component.

20 The bolt of the present invention eliminates the need for a separate expansion device and hence is less costly to make and assemble than some of the prior bolts discussed above. Furthermore, since the bolt can be completely assembled prior to shipment, there is less handling at the mine site and hence it is less costly to install.

Even though it is preferred to make the bolt of the present invention of steel, it can be made of a lighter, less corrosive material by reason of its design.

The bolt of the present invention, in addition to being 30 easy and quick to install, may be easily removed after a period of time and reused and indefinite number of times.

With the foregoing in mind, an object of the present invention is to provide a roof bolt for use particularly as a 35 support means for mine roofs which is characterized by novel features of construction and arrangement providing a firm support for the mine roof.

Another object of the present invention is to provide 40 a roof bolt which firmly grips the strata of the roof essentially throughout its length, thus substantially eliminating anchor slippage and minimizing the harmful effect of bolt elongation.

Another object of the present invention is to provide 45 a roof bolt which pre-stresses the strata or layers of materials above the roof laterally so that a pattern of these bolts arranged in the mine supports the compression as well as the tension component of shear stress in the roof layers.

A further object of the present invention is to provide 50 a bolt which may be economically and easily manufactured, which is also easy to remove and which can be reused many times.

These and other objects of the present invention and the 55 various features and details of the construction and use thereof are hereinafter more fully set forth with reference to the accompanying drawings, wherein:

FIG. 1 shows a section of roof strata with a bolt in accordance with the present invention mounted therein;

FIG. 2 is a view taken on line 2—2 of FIG. 1 showing 60 a section of the roof with a plurality of bolts in accordance with the present invention installed therein;

FIGS. 3 and 4 are enlarged sectional views taken on lines 3—3 and 4—4 of FIG. 1;

FIG. 5 is an enlarged fragmentary view similar to FIG. 61 showing the bolt in the expanded operative position engaging the side wall in the hole in the roof;

FIG. 6 is an enlarged sectional view taken on lines 6—6 of FIG. 5;

FIGS. 7 and 8 are fragmentary perspective views of a 70 bolt in accordance with the present invention in the stacked and expanded positions respectively;

FIG. 9 is a fragmentary perspective view of one of the elements of a bolt in accordance with the present invention;

FIG. 10 is a side elevational view of another embodiment.

ment of mine roof bolt constructed in accordance with the present invention;

FIGS. 11, 12 and 13 are sectional views of the mine roof bolt assembly of FIG. 10 taken on lines 11—11, 12—12 and 13—13 respectively;

FIG. 14 is an enlarged section of a roof strata with the mine roof bolt in accordance with the present invention mounted therein;

FIG. 15 is a sectional view through the bolt taken on line 15—15 of FIG. 14;

FIG. 16 is a fragmentary exploded perspective view of the bar members comprising the second embodiment of bolt;

FIG. 17 is a fragmentary layout of one of the bar members in a stage of manufacture;

FIG. 18 is a schematic illustration showing a method for making the bar members of the mine roof bolt shown in FIG. 10;

FIGS. 19 and 20 are fragmentary views of one of the bar members of the mine roof bolt at various stages of manufacture;

FIG. 21 is a view taken on line 21—21 of FIG. 20;

FIG. 22 is a sectional view of stock material from which the other bar member of the bolt is made;

FIG. 23 is a fragmentary side elevational view of the other bar member at a stage of manufacture; and

FIG. 24 is a view taken on lines 24—24 of FIG. 23.

Referring now to the drawing and particularly to FIG. 1 thereof, there is shown a typical cross section of the roof of a mine passageway or tunnel which as illustrated is comprised of several strata or layers L. A mine roof bolt 10 in accordance with the present invention is mounted in a vertically extending hole 11 in the roof strata. These bolts are adapted to be inserted in the roof at predetermined spaced apart locations usually about three to four feet apart as illustrated in FIG. 2, and when in the expanded anchored position, the bolts serve to pre-stress the strata laterally thereby supporting the compression as well as the tension component of shear stress in the various layers comprising the roof, and thereby minimizing flexure and thus, preventing roof failure.

Considering now the specific details of construction, the bolt 10 comprises a pair of elongated bar members 12 and 14 having confronting interengaging inner faces 13 and 15 respectively. The face 13 is of a stepped configuration comprising a plurality of angularly disposed, longitudinally spaced flat cam surfaces 18 and a plurality of short radially directed shoulders 19, each shoulder 19 connecting adjacent cam surfaces 18. The face 15 of the bar 14 is also of a stepped configuration comprising a plurality of angularly disposed, longitudinally spaced, flat planar cam surfaces 20 and a plurality of radially directed shoulders 21 connecting adjacent cam surfaces. The cam surfaces 18 and 20 are approximately of equal length so that the bar members nest snugly together when in the stacked position shown in FIG. 1. As best illustrated, the cam surfaces 18 and 20 are disposed at a slight angle to the longitudinal axis of the bar members and the shoulders 19 and 21 seat against one another in the stacked position to limit relative longitudinal movement of the bar members in one direction.

Each bar member as best illustrated in FIGS. 7—9 inclusive, has a rounded outer side wall opposite the cam face, the outer wall 30 of the bar 12 having a plurality of longitudinally spaced cutouts 31 defining a plurality of longitudinally spaced projections which comprise contact zones Z₁, adapted to engage the side wall of the opening 11. As best illustrated in FIG. 9, the cutout in the outer side wall is at an angle relative to a longitudinal axis of the bar member to form a series of triangularly shaped planar faces 33 approximately parallel to the cam surfaces 18. The bar 14 also has a rounded outer side wall 40 with a plurality of longitudinally spaced cutouts 41 defining longitudinally spaced projections which comprise contact zones Z₂ adapted to engage the side wall of the hole or

opening 11. These cutouts 41 are also angularly directed to form a series of triangularly shaped faces 43 approximately parallel to the cam surfaces 20. By this arrangement, as best illustrated in FIG. 1, the contact zones Z₁ and Z₂ are slightly staggered on either side of a plane transverse to the axis of the bar in the stacked position. In the present instance as illustrated in the drawings, the spacing between substantially all of the adjacent contact zones is at least equal to the largest cross sectional dimension measured in a plane perpendicular to the longitudinal axis of the bolt in the stacked position.

The bar members are adapted for longitudinal movement relative to one another between a stacked or closed position (see FIG. 1) and an expanded position (see FIG. 15). In the stacked position, the maximum cross sectional dimension D of the bolt or the distance between contact zones Z₁ and Z₂ is the smallest to facilitate insertion into the hole 11 of a mine roof. In the expanded position (see FIG. 5) the contact zones Z₁ and Z₂ are displaced laterally due to interengagement of the cam surfaces to a distance apart greater than D. In order to facilitate longitudinal movement of the bars, the bar member 14 is provided with a threaded shank 50 depending from its lower terminal end which is of a cross section smaller than the greatest cross section of the bar to define an abutment shoulder 52 adjacent its lower end. The other bar member 12 has a depending stem 56 which in the stacked position of the bar members (FIG. 7) projects downwardly beyond the shoulder 52. The lower end of the stem 56 is spaced from the terminal end of the shank 50 to expose a portion of the threaded shank thereby to accommodate a plate 60 and nut 62.

In the installation of a bolt in accordance with the present invention, the bar members are initially in the stacked position shown in FIGS. 1, 3 and 7, wherein the cam surfaces 18 and 20 are in confronting relation for their entire length and the stem 56 projects downwardly beyond the shoulder 52 of the threaded shank 50. The bar members may be detachably held in this stacked position simply by wrapping tape around the bar members at selected locations along their length. The bolt in its stacked position is then inserted up into the opening 11 in the mine roof, the opening being of a slightly greater cross sectional dimension than the greatest cross section D of the bolt in its stacked position to provide a very small clearance therebetween. For example, for an opening 11 having a diameter of about 1.375 in., the distance D between the contact zones Z₁ and Z₂ of the bar members is approximately 1.250 in. Thereafter, the bearing plate 60 is positioned over the threaded shank 50 and the nut 62 is threaded on the shank 50. Now, as the nut 62 is tightened against the bearing plate 60, the bar member 14 is displaced longitudinally downwardly relative to the bar member 12. Relative longitudinal displacement of bar members causes relative lateral displacement of contact points or zones Z₁ and Z₂ due to the interaction of the cam surfaces 18 and 20 whereby the side wall of the opening 11 is engaged at a plurality of longitudinally spaced points along the length thereof as best illustrated in FIG. 5. By this arrangement, when a series of bolts is installed in the roof at their predetermined spaced apart locations in the manner shown in FIG. 2, the layers L of the roof strata are prestressed in a lateral direction for a substantial height above the roof level whereby the compression and the tension components of shear stress in the layers or strata L are supported. In this manner a firm support is provided. Now, when it is desired to remove the bolts, the nut 62 is simply threaded off the shank 50, the plate 60 is removed and then merely by tapping the free terminal end of the shank 50 upwardly, the bar members are urged to a stacked position whereby they may be easily removed from the opening in the roof.

The roof bolts of the present invention may be made relatively economically. For example, the bolt may be made by die stamping, forging or rolling.

There is shown in FIGS. 10—17 another embodiment of

mine roof bolt 100 in accordance with the present invention. The specific details and construction of the bolt are best illustrated in FIGS. 10, 14 and 16, and as illustrated therein, the bolt 100 comprises a pair of elongated bar members 102 and 104 having confronting interengaging inner faces or surfaces 106 and 108 respectively of a predetermined configuration whereby upon relative axial displacement of the bar members, the members may be actuated from a stacked position (see FIG. 10) for insertion into a hole or opening 110 in the roof strata to an expanded position (see FIG. 14) wherein the opposing outer surfaces of the members are displaced laterally into pressure-applying relation with the side wall of the opening 110 in the roof strata.

To this end, the bar member 102 which may be of half-moon cross section and of a serpentine shape, has an inner surface or face 106 of stepped configuration comprising a plurality of angularly disposed longitudinally spaced planar or flat cam surfaces 112, each cam surface 112 terminating in a rounded edge and merging with a plurality of short angularly directed shoulders 114, each shoulder connecting adjacent cam surfaces 112. The outer surface or face 117 of the bar member 102 is also of a stepped configuration defining a plurality of longitudinally spaced projections defining contact zones Z_{11} adapted to engage the side wall of the opening 110 in the roof strata at a plurality of spaced locations. In the present instance as illustrated in the drawings, the spacing between substantially all of the adjacent contact zones Z_{11} is at least equal to the largest cross sectional dimension measured in a plane perpendicular to the longitudinal axis of the bolt in the stacked position.

The bar member 104, in the present instance, is an elongated hollow member of generally U-shaped cross section having longitudinal spaced apart side edges 117a and 117b of a stepped configuration to define a plurality of angularly disposed, longitudinally spaced flat cam surfaces 120 and a plurality of short, angularly directed shoulders 122, each shoulder merging with adjacent cam surfaces 120 in a rounded edge and connecting adjacent cam surfaces 120. In the present instance, the outer face of the bar member 104 is a continuous surface defining one continuous contact zone Z_{12} extending the length of the bar member 104. The cam surfaces 112 and 120 of the bar members are approximately of equal length so that the bar members nest snugly together when in the stacked position shown in FIG. 10. As illustrated, the cam surfaces 112 and 120 are disposed at a slight angle to the longitudinal axis of the bolt and the shoulders 114 and 122 seat against one another in the stacked position to limit relative longitudinal movement of the bar members in one direction.

The bar members are adapted for relative longitudinal movement between a stacked or closed position and an expanded position and in the stacked position the maximum cross sectional dimension D' of the bolt or the distance between the contact zones Z_{11} and Z_{12} at any point along the length of the bolt is smaller to facilitate insertion into the hole 110 of the roof strata. In the expanded position, the contact zones are displaced laterally due to interengagement of the cam surfaces to a distance apart greater than D' . The means for effecting longitudinal movement of the bars includes, in the present instance, a threaded shank 127 depending from the lower terminal end of the bar member 104 which is of a cross section smaller than the outer cross section of the bar member to define an abutment shoulder 129 adjacent its lower end. The bar member 102 has a depending stem 130 which in the stacked position of the bar members projects downwardly beyond the shoulder 129 so that its lower end is spaced from the terminal end of the shank to expose a portion of the threaded shank 127 to accommodate a plate 132 and nut 134.

In the installation of bolt of the type described above, the bar members 102 and 104 are initially in the stacked

position shown in FIG. 10, being held in that position by means of strips of tape 135 at longitudinally spaced points. It is noted that the bolt is delivered to the mine site in this condition thereby obviating the need for any time-consuming assembly operation. Furthermore, the assembly is comparatively light thereby facilitating handling in the mines. In its stacked position, the bolt is then inserted up into the opening 110 in the mine roof, the opening 110 being of a slightly greater cross sectional dimension than the greatest cross section D' between the contact zones Z_{11} and Z_{12} . With the bolt so positioned, the nut 134 is turned to effect relative longitudinal displacement of the bar members. This longitudinal displacement effects lateral displacement of the contact zones Z_{11} and Z_{12} due to the interaction of the cam surfaces 112 and 120 whereby the side wall of the opening is engaged at a plurality of longitudinally spaced points of the bar member 102 and the contact zone Z_{12} of the other bar member 104 engages the side wall of the other opening along its entire length. By this arrangement, when a series of bolts is installed in the roof at a plurality of predetermined spaced apart locations, the layers of the roof strata are pre-stressed in a lateral direction for a substantial height above the roof level whereby the compression and tension components of shear stress in the layers are supported. It is noted that this bolt arrangement provides for a large gripping area. Furthermore, bolt elongation is minimized due to the continuous area of contact between the bolt and the wall of the hole. Thus, forces developing between adjacent layers of strata are supported by a relatively short length of bolt and elastic elongation is therefore minimal. The bolts may be removed from the mine when desired simply by threading down the nut 134 and tapping the free terminal end of the shank 127 whereby the bars are urged to a stacked position. It is noted that if an elastic tape is used, the tape retains the bar members in the stacked position when removed from the roof to facilitate reuse. The specific configuration of the mine roof bolt shown in FIGS. 10-17 inclusive and more particularly the provision of the tubular bar member 104 minimizes the possibility of flattening out of the confronting cam surfaces accordian-style which would tend to reduce the effective gripping force of the mine roof bolt when assembled in an opening in the roof of a mine. This construction also minimizes bolt elongation, which, as noted above, is an important factor contributing to failure of the roof.

Another feature of the present invention is the provision of a simple and economical means for manufacturing a mine roof bolt of the type illustrated in FIGS. 10-16. In accordance with the present invention, the bar member 104 may be formed by bending an elongated flat strip having a predetermined, irregular side edge configuration to a generally circular shape so that the side edge portion define the cam surface and shoulders. In the preferred method of the present invention the bar member 104 may be formed from flat sheet stock by cutting the sheet into a plurality of strips having the desired edge configuration to define the cam surfaces and shoulders. Thereafter, each individual flat strip is formed, for example, by a rolling process to the U-shaped configuration as shown in FIG. 16, the continuous rolled strip then being cut to size by suitable means. The other bar member 102 may be formed from a continuous piece of bar stock having a half-moon cross section by a bending operation in a joggle mill or the like to define the configuration shown having the series of adjacent angularly disposed cam surfaces. This zig-zag or serpentine piece of bar stock is then suitably cut to size and assembled to the other bar member and held thereto by means, for example, of a series of adhesive strips. The bolt is now ready for use. It is noted that, as mentioned above, the adhesive may be a flexible type so that when the bolt is used in a mine roof, the adhesive does not sever and

remains in place when the bolt should be removed from the hole in the mine roof for reuse.

There is illustrated schematically in FIG. 18 a method for making and assembling a mine roof bolt in accordance with the present invention. As illustrated therein, there are two separate assembly lines A and B for making the respective bar members 104 and 102 of the roof bolt. In line A, flat sheet stock 150 is fed to a cutting device 152 such as a torch cutting apparatus or a plurality of cooperating disc-like cutting knives to cut the sheet 150 longitudinally into a plurality of side by side strips 154 having a serpentine or corrugated side edge configuration to define the cam surfaces 120 and connecting shoulders 122 when the strip is rolled. The strips 154 are then taken up on a plurality of take-up rolls at a storage or recoiler station 156, the roll assembly being mounted on trackways so that a selected roll may be positioned in registry with the remainder of the stations in line A. It is noted that the direction of feed from the storage rolls for alternate strips has to be reversed for proper orientation at a later time at the assembly station with the other bar member.

As a strip 154 is wound from the storage roll, it passes through an uncoiling device 158 and a leveler 160 to a prenotch press 162, where, as illustrated in FIG. 19, the strip 154 is cut part way through transversely to its axis at predetermined spaced apart intervals which define the length of the bar. The strip 154 is then formed into a circular cross section of generally U-shaped configuration in a roll forming mill 164 and from there, the rolled up strip 154 passes through the cutoff press 166 where the rolled up strip is severed at the prenotched points to form the bar member 104. The threaded stud 127 is then assembled to each of the individual bar members 104 at an automatic welding station 170.

The bar member 102 of the bolt is formed on line B in FIG. 18 and as illustrated therein a continuous piece of stock 172 of half-moon cross section is fed through an uncoiler 174 to a leveler 176 and then is fed into a joggle mill 178. In the joggle mill 178, the flat bar stock 172 is deformed by suitable means to the serpentine configuration illustrated in FIG. 18. The so deformed bar leaves the joggle mill and passes through a cutoff press 180 where the bar is cut into suitable lengths and one end of the bar is straightened out to define the stem. The completed bar is then transferred to the automatic assembling station 182 where it is mated with a bar 104 and the tape 135 is applied at preselected points so that the finished assembly is ready for use.

From the above, it is readily apparent that the present invention provides a comparatively simple and highly economical method for manufacturing mine roof bolts. By the method of the present invention there is comparatively little waste since no machining operations are required to produce the bolt. Further, substantially all of the manufacturing and assembly operations may be carried out on automatic equipment thereby reducing labor costs. Even though the preferred material for making the bolt is steel, other materials such as fiberglass reinforced plastic may be used.

While the bolt of the present invention is primarily used in mines for supporting the roof of the mine, it is to be understood that it may be used effectively in other underground passageways to support the overlying strata. Additionally, the bolt has other useful applications, for example, in certain road excavation operations the bolt may be used to prevent rock slides.

While particular embodiments of the present invention have been illustrated and described herein, it is not intended to limit the invention and changes and modifications may be made therein within the scope of the following claims. For example, the coefficient of friction between one or both the bar members and the wall of the opening in the mine roof may be increased by roughening the surfaces of the bar members confronting and engaging

the wall of the hole, for example, by knurling, ridging or other suitable roughening means. Additionally, the internal friction between the confronting cam surfaces of the bar members may be reduced by suitable permanently applied lubricant means to the cam surfaces.

I claim:

1. A bolt adapted to be mounted in an elongated opening in the roof of a mine comprising a pair of elongated bar members, the inner surface of one of said bar members having a plurality of spaced angularly disposed cam surfaces, the other bar member being of generally U-shaped cross section and having longitudinal, spaced apart side edges of stepped configuration to define a plurality of longitudinally spaced cam surfaces angularly disposed in the same direction as the cam surfaces of said one bar member, means for effecting longitudinal displacement of said bar members between a stacked position wherein the bar members are nested together and an expanded position whereby the outer side walls of the bar members opposite said cam surface are displaced laterally into pressure-applying relation with the side wall of the opening, the outer surface of said one bar member having a plurality of longitudinally spaced projections defining a plurality of longitudinally spaced contact zones adapted to engage the side wall of the opening upon displacement of the bar members to the expanded position, the spacing between substantially all of the adjacent contact zones being at least equal to the largest cross sectional dimension measured in a plane perpendicular to the longitudinal axis of the bolt in the stacked position.

2. A mine roof bolt as claimed in claim 1 wherein said one bar member is of half-moon cross section and of serpentine shape having an inner surface of stepped configuration comprising a plurality of angularly disposed longitudinally spaced planar cam surfaces, each of said cam surfaces terminating in a rounded edge and merging with a plurality of angularly directed shoulders, said shoulders connecting adjacent cam surfaces and wherein the outer surface of said one bar member is also of stepped configuration defining a plurality of longitudinally spaced projections defining contact zones adapted to engage the side wall of the opening upon displacement of said bar members to the expanded position.

3. A mine roof bolt as claimed in claim 1 wherein the side edges of said other bar member include a plurality of angularly disposed longitudinally spaced flat cam surfaces and a plurality of short angularly directed shoulders merging with adjacent cam surfaces in a rounded edge and connecting adjacent cam surfaces.

4. A mine roof bolt as claimed in claim 1 wherein one bar member has a longitudinally directed stem projecting from one end thereof and the other bar member has a longitudinally directed threaded shank projecting from one end thereof, and including internally threaded means mounted on said shank to engage said stem to effect longitudinal relative movement of said bar members.

5. A bolt adapted to be mounted in an elongated opening in the roof of the mine comprising a pair of elongated bar members having confronting longitudinally extending faces, the face of one of said bar members being of a stepped configuration and comprising a plurality of longitudinally spaced angularly disposed cam surfaces, adjacent cam surfaces being connected by flat shoulders extending transverse to the longitudinal plane of the bar members, the other of said bar members being also of a stepped configuration and comprising a plurality of longitudinally spaced angularly disposed cam surfaces, adjacent cam surfaces of said other bar member being connected by flat shoulders extending transversely to the longitudinal plane of the bar member, each bar member having a side wall opposite the cam face having a plurality of longitudinally spaced projections defining contact zones, means for effecting longitudinal displacement of said bar members between a stacked position wherein the cam surfaces are confronting and coextensive and the distance between

opposed contact zones is minimum and of a smaller dimension than the cross section of the opening to permit the bolt to be inserted into the opening and a stacked position whereby the cam surfaces cooperate to effect lateral displacement of the bar members and engagement of the respective contact zones with the side wall of the opening thereby to engage the opening at a plurality of longitudinally spaced points along the entire length thereof, the spacing between substantially all of the adjacent contact zones being at least equal to the largest cross sectional dimension measured in a plane perpendicular to the longitudinal axis of the bolt in the stacked position.

6. A mine roof bolt as claimed in claim 5 wherein the contact zones are defined by a plurality of cutouts in the side wall of the bar members which extend at an angle relative to the longitudinal axis of the bar to form series of triangularly shaped planar faces approximately parallel to the cam surfaces.

7. A mine roof bolt as claimed in claim 5 wherein the outer side wall is rounded.

8. A bolt adapted to be mounted in an elongated opening in the roof of a mine comprising a pair of elongated bar members having inner confronting longitudinally extending surfaces, the inner surface of each of said bar members having a plurality of longitudinally spaced cam surfaces which are angularly disposed in the same direction, adjacent cam surfaces being connected by shoulders, means for effecting relative longitudinal displacement of said bar members from a stacked position wherein the bar members are nested together and an expanded position whereby the outer surfaces of the bar members opposite said cam surfaces are displaced laterally into pressure applying relation with the side wall of the opening and means defining a plurality of longitudinally spaced projections on the outer face of at least one of said bar members providing a plurality of longitudinally spaced contact zones adapted to engage the side wall of the opening upon displacement of the bar members to an

expanded position, the spacing between substantially all of the adjacent contact zones being at least equal to the largest cross sectional dimension measured in a plane perpendicular to the longitudinal axis of the bolt in the stacked position.

9. A bolt as claimed in claim 8 wherein both of said bar members are of half-moon cross section and wherein the outer surface of each bar member is of stepped configuration to define a plurality of longitudinally spaced projections providing longitudinally spaced contact zones.

10. A mine roof bolt as claimed in claim 8 wherein one bar member has a longitudinally directed stem projecting from one end thereof and the other bar member has a longitudinally directed threaded shank projecting from one end thereof, and including internally threaded means mounted on said shank to engage said stem to effect longitudinal relative movement of said bar members.

11. A mine roof bolt as claimed in claim 8 wherein at least one of said bar members is of half-moon cross section and wherein the outer surface of said one bar member is of a stepped configuration to define a plurality of longitudinally spaced projections providing a plurality of longitudinally spaced contact zones adapted to engage the side wall of the opening upon movement of said bar members to the expanded position.

CERTIFICATE OF CORRECTION

Patent No. 3,301,123

January 31, 1967

William E. Worley

It is hereby certified that error appears in the above numbered patent requiring correction and that the said Letters Patent should read as corrected below.

Column 1, line 42, for "he" read -- the --; column 2, line 46, for "turining" read -- turning --; column 3, line 5, for "takens" read -- takes --; column 4, line 31, for "and", second occurrence, read -- an --; column 5, line 23, strike out "from"; line 64, for "outer" read -- outer side --; column 10, line 7, for "in", second occurrence, read -- an --; column 11, line 3, for "stacked" read -- expanded --.

Signed and sealed this 17th day of October 1967.
